BOTTLE OPENER

Ronald C. Roeschlaub, Los Angeles, Calif., assignor to
Topper Products, Inc., Los Angeles, Calif., a corpora-
tion of California

Filed Aug. 26, 1965, Ser. No. 86,732

Term of patent 14 years

(Cl. D44—29)

FIG. 1.

FIG. 2.

FIG. 3.

FIG. 4.

FIG. 1 is a perspective view of a bottle opener showing my new design;

FIG. 2 is a front elevational view thereof;

FIG. 3 is a fragmentary sectional view thereof, slightly enlarged from the scale of FIGS. 1 and 2, taken in the plane indicated by line III—III of FIG. 2;

FIG. 4 is an enlarged scale sectional view taken in the plane indicated by line IV—IV of FIG. 2.

The essential features of my design are shown in full lines on the drawing.

I claim:

The ornamental design for a bottle opener, as shown and described.
